Patented Aug. 13, 1918.

UNITED STATES PATENT OFFICE.

GUY M. OVERTREE, OF FORT COLLINS, AND VOLLEY V. McMILLEN, OF LAFAYETTE, COLORADO.

BRACE.

1,275,593.

Specification of Letters Patent. Patented Aug. 13, 1918.

Application filed February 21, 1917. Serial No. 150,149.

To all whom it may concern:

Be it known that we, GUY M. OVERTREE, a citizen of the United States, residing at Fort Collins, in the county of Larimer and State of Colorado, and VOLLEY V. McMILLEN, a citizen of the United States, residing at Lafayette, in the county of Boulder and State of Colorado, have invented certain new and useful Improvements in Braces, of which the following is a specification.

This invention relates to improvements in braces and its primary object resides in providing in combination with a crank for rotating tools, nuts and screws, means by which the rotation of an object to which the crank is applied may be effected independent of the crank movement for the purpose of applying and tightening nuts and screws at points located so as to forbid the use of an ordinary brace, wrench or screw-driver.

Our invention may also be effectively used as a substitute for the hand in applying nuts to studs or bolt-ends and it greatly facilitates the subsequent placement of the brace in its proper position with relation to the nuts.

With the above object in view we provide in association with a brace of standard construction, a movement transmitting mechanism by which the socketed holding member of the instrument may be rotated independent of the crank on which it is mounted.

The transmission hereinbefore referred to, consists of a worm gear and worm which are connected respectively with the holding member of the brace and with a shaft rotatably mounted on the brace crank at an angle to the axis of rotation of the same.

In the accompanying drawings in the various views of which like parts are similarly designated,

Figure 1 represents an elevation of a brace to which our invention is applied,

Fig. 2, a section along the line 2—2, Fig. 1,

Fig. 3, a front view of the end of the brace at which the holding member is connected, looking in the direction of the arrow A, Fig. 1, and

Fig. 4, a section taken along the line 4—4, Fig. 2, drawn to an enlarged scale.

Referring to the drawings by numerical reference characters, 2 designates the crank of a brace of ordinary construction which at

the end of one of its arms connects with a

swiveled head 3 and which carries at the end of its opposite arm in axial alinement with said head a member adapted to hold the tool, nut or screw to be applied by rotation of the crank about the axis of the head.

In the construction shown in the drawings, the holding member comprises a socketed chuck 4 at the end of a shank 5 of angular section which is removably fitted in the hub 6 of a worm gear 7.

The hub of the gear is rotatably fitted in a keeper 8 which by means of an integral thimble 9 and a pin 10, is rigidly secured at the end of the brace arm 12 opposite to that which connects with the swiveled head, and a screw 13 projects through a threaded aperture of the keeper into a circumferential groove of the hub to hold the worm-gear against axial displacement.

With the parts thus relatively positioned the coincident axes of the socketed chuck 4 and the worm-gear 7 are in alinement with the axis of rotation of the head 3.

A worm 14 co-operative with the worm wheel is mounted at the end of a shaft 15 which extends parallelly alongside the arm 12 of the brace to which the keeper is applied.

The shaft has at its outer end a crank 16 to facilitate its rotation and it is rotatably supported in two bearings 17 and 18 one of which is secured to the brace arm and the other one of which is formed integral with the keeper 8.

The last-mentioned bearing is as best shown in Fig. 2, preferably composed of two parts between which the worm is disposed.

Having thus described the mechanical construction of our invention, its uses and advantages will be readily understood.

To apply a nut to a threaded stud or bolt, the nut may be placed in the socket of the holding member and thus brought in contact with the end of the threaded object without touching the same with the hand.

Premising that the position of the bolt or stud with relation to adjacent parts or objects is such that it is impossible to effect a complete rotation of the brace crank, the socketed holder in which the nut is held, is by means of the worm-movement rotated independent of the crank movement until the nut is driven home.

The nut may subsequently be tightened by

imparting a partial rotation to the brace crank, which can be done repeatedly without removing the holder from the nut or displacing the latter by returning the crank after each rotative movement, to its original position through the instrumentality of the worm movement.

It will thus be seen that the latter in addition to effecting the rotary movement of the holding member, independent of the crank motion of the brace, also serves as an equivalent for the appliances used in braces of the ratchet type for rotating the tool or nut-holder by a succession of partial rotations of the crank of the same.

In applying the brace to a nut or angular bolt-head the socketed chuck can be readily adjusted to fit the same by rotation of the crank.

Having thus described our invention what 20 we claim and desire to secure by Letters-Patent is:

A brace comprising a crank including a laterally projecting arm and a bearing at the end thereof, a worm gear mounted for rotation in said bearing, a holder connected for rotation with said worm wheel, a rotary shaft extending along said arm, a worm at one end of said shaft, in mesh with said gear, and a crank at the opposite end of the shaft to effect its rotation. 25 30

In testimony whereof we have affixed our signatures in presence of two witnesses.

GUY M. OVERTREE.
VOLLEY V. McMILLEN.

Witnesses:

G. J. ROLLANDET,
L. RHOADES.
